ATTORNEY

UNITED STATES PATENT OFFICE.

PAUL P. LANGNER, OF MINNEAPOLIS, MINNESOTA.

COMBINATION CANE OR THE LIKE AND SIGNAL.

Application filed October 2, 1924. Serial No. 741,121.

To all whom it may concern:

Be it known that I, PAUL P. LANGNER, a citizen of the United States, residing at Minneapolis, in the county of Hennepin and 5 State of Minnesota, have invented certain new and useful Improvements in Combination Canes or the like and Signals, of which the following is a specification.

This invention relates to devices used in 10 guiding and aiding physically afflicted people and the main object is to provide an improved construction of cane and means in connection therewith serving as a stop signal, whereby a blind or crippled person may 15 signal motorists and others so as to give him the right of way when crossing a street or street intersection. Further and more specific objects will be disclosed in the course of the following specification, reference being had to the accompanying drawing, in which:

The single figure shows an elevation of a cane or staff embodying my invention.

Although a cane, as the term is commonly 25 used, is shown in the drawing and described throughout the specification and claims, it will be understood that any similar device such as a staff, walking stick, crutch, umbrella, or the like, may be used in the same 30 manner and for the same purposes, and to that extent the term "cane" will be understood as a broad term to include and embrace any of such devices.

The cane I have illustrated consists of a 35 rigid rod A, having a curved handle B at its upper end. At its lower end the cane is provided with a rigid member C in which is mounted a roller D, the forked portion of the member being offset, as at E, in the same 40 plane with the handle B, so that when the cane is held in its normally inclined position, as shown, the roller will properly engage the floor or sidewalk on which the afflicted person is walking.

Secured upon, and near the lower end of 45 the cane rod A, by suitable means such as collars F, a sign G. This sign is preferably red so as to be clearly distinguishable as a

signal or semaphore, and on it is written or 50 printed suitable words such as "Blind," "Cripple," "Disabled" or "Stop," so as to properly warn drivers of vehicles to be careful and give the right of way to the person holding the cane. The sign may be provided with suitable lighting or illuminating 55 lights (not shown) so that it will be equally effective at night.

If the word "Blind," for instance, is arranged longitudinally of the sign plate, it 60 may be raised to a horizontal or correct reading position as the person crosses the street. This sign is preferably on the opposite side from the handle, so that the holder of the cane, if blind, will know that the sign is in a vertical plane position when 65 he grasps the handle in its normal or rearward position, as shown.

When walking on a floor or sidewalk where there is no particular danger of 70 vehicular traffic, the blind person may keep the roller in constant engagement with the ground, and will not have to pick or feel his way as with an ordinary cane, and in this manner will be kept informed of the surface condition he is treading or advancing 75 upon.

It is understood that various modifications 80 may be made in the general design and structural details of the device as herein disclosed, provided, however, that such modifications come within the spirit and scope of the appended claims.

Having now therefore disclosed my invention what I claim is:

1. A cane, having a handle at its upper end, a sign plate secured near the lower end of the cane, said sign plate and handle projecting from the cane in a common plane.
2. A cane, having a handle at its upper end, a sign secured near the lower end of the cane, said sign and handle projecting from the cane in a common plane but at opposite sides of the cane.

In testimony whereof I affix my signature.

PAUL P. LANGNER.
